MANUFACTURE OF SHOES HAVING
STIFFENED PARTSStanley P. Lovell, Newton, Mass., assignor to
Arden Box Toe Company, Watertown, Mass., a
corporation of Massachusetts

Application December 5, 1932, Serial No. 645,649

7 Claims. (Cl. 12—145)

This invention relates to the manufacture of shoes having stiffened parts, for instance, a stiffened fore part and/or a stiffened back or rear part.

5 In making shoes having stiffened parts, it has heretofore been the practice to introduce under the upper leather of the shoe a stiffener blank which prior to the lasting operation was made limp and moldable by suitable treatment so as 10 to be conformable to the shape of the last. Such a blank was pre-formed or pre-cut to the desired shape and was skived accurately at its marginal portions to render the inside of the shoe smooth and comfortable as well as to avoid unsightly 15 ridges on the surface of the finished shoe. The stiffener blank usually consists of an integral fibrous sheet serving as a carrier for a stiffening agent of a colloidal nature. It is common practice to impregnate a fibrous sheet with such stiffening agent, to cut the stiffener blank from the 20 impregnated sheet, and finally to skive the blank at its marginal portions to a feather edge. The blank in this form reaches the shoe operator who renders it limp and moldable by the application 25 of moderate heat or by solvent action, depending upon the nature of the stiffening agent. The operator then assembles the moldable blank with the shoe upper and performs the lasting and 30 pulling-over operations which impart to the blank its desired permanent shape.

In accordance with the present invention, rather than depending upon the introduction of a pre-formed stiffener blank into the shoe upper, the desired stiffening effect is realized by charging with stiffening agent at the desired zones the woven or other fabric which invariably is associated with the shoe upper as a doubler and/or lining. In accomplishing this result, I first treat 35 the desired zone or locality of the doubler and/or lining with a solvent or gelatinizing liquid for the particular stiffening agent to be employed and then associate with the liquid-treated zone the stiffening agent under conditions resulting in a substantially complete solution or fusion of the 40 agent, in consequence of which the agent flows into the treated zone, and, upon the evaporation of the solvent or gelatinizing liquid, functions to stiffen such zone. Before such stiffening action 45 has ensued, however, the liquid-treated zone together with its associated dissolved or fused stiffening agent is conformed to the shape of the last in the course of the usual shoe-making operations. By such practice, I may, for example, effect a stiffening of the toe portion of the 50 shoe, the stiffening agent existing in the doubler 55

and/or lining invariably forming part of the shoe upper assembly.

There are various ways of applying the principles of my invention. Let us assume, for example, that a shoe upper assembly is on the last and is ready to be stiffened at its toe portion prior to conformation to the last. In accordance with my invention, the toe portion of the doubler and/or lining of the upper assembly is treated by immersion, spraying, or other suitable treatment with a suitable solvent or gelatinizing liquid for the stiffening agent, the fabric constituting the doubler and/or lining thereby becoming charged with solvent or gelatinizing liquid. A film of the proper stiffening material is now laid 15 on the wet doubler and/or lining and the upper assembly is then put through the pulling-over and bed-lasting operations. There are various combinations of solvent or gelatinizing liquid and films of stiffening material which might be used 20 in the practice of my invention. For instance, the doubler and/or lining can be treated with acetone, and films of cellulose acetate or cellulose nitrate may be used as the stiffening media. If desired, a film of gelatin may be used as the 25 stiffening medium, in which case, the doubler and/or lining may be treated with water or dilute acetic acid as the solvent or gelatinizing liquid. By using a solvent or gelatinizing liquid of the proper kind and by associating therewith a 30 comparatively thin film of the stiffening medium, it is possible to sever the excess film lying outside of the solvent-affected film area before or after the pulling-over and bed-lasting operations have been completed. Indeed, a properly wet 35 doubler and/or lining may be laid on a film or between two films of stiffening medium, the other parts of the shoe assembly brought together over the film, and a film blank corresponding to the wet zone of the doubler and/or lining removed 40 from the rest of the film. In other words, the solvent or gelatinizing liquid will etch or cut away from a sheet of film material, as if by knife or die action, the desired area of film material, for instance, an area corresponding to the toe portion 45 of the upper. Rather than using a film for furnishing the stiffening medium to the wet doubler and/or lining, it is possible to apply solid powdered stiffening medium thereto. For instance, the wet area of the doubler and/or lining 50 may be brought into contact with a mass of such powder or the powder may be sifted or projected on such area from a spray gun or atomizer. In such case, however, there may be difficulty in realizing a uniform stiffening effect. The use 55

of the stiffening medium in film form, however, makes possible speed of operation, uniform results, and no soiling or smudging of the shoe upper parts.

With the foregoing and other features and objects in view, my invention will now be described in conjunction with the accompanying drawings, wherein,—

Figure 1 represents in plan view, before the lasting operation, a shoe upper assembly, the toe portion of the upper being lifted away from the doubler and lining to show the solvent-treated area.

Figure 2 is a similar view with a film placed over the solvent-treated area.

Figure 3 illustrates diagrammatically the blowing of powdered stiffening medium over the solvent-treated toe portion.

Figure 4 shows in perspective the bottom of the toe portion after the pulling-over operation has been completed, with the excess film being removed at the margins of the shoe upper.

Figures 5 and 6 are enlarged sections through the stiffened parts of a shoe and illustrate the end results in the case of stiffening agent used in film and powdered form respectively.

Figure 7 is a side view of a shoe stiffened at its fore part in accordance with my invention, the fore part being shown in section.

While the drawings illustrate the stiffening of the fore part of a shoe in accordance with my invention, it is of course possible to stiffen other parts, for instance, the back or rear part, and thus dispense with the use of a so-called counter. As shown in Figure 1, the toe portion 1 of the doubler and/or lining of the shoe upper assembly may be thoroughly wet with a solvent or gelatinizing liquid, e. g., acetone, when cellulose acetate or cellulose nitrate is to serve as the stiffening medium. A film 2 of the stiffening medium may then be laid upon the solvent-treated area. Should there be excess film material outlying the solvent-treated area, as shown in Figure 2, this excess may be readily removed by bringing the upper 3 and the other parts of the upper assembly together, for, as hereinbefore observed, the solvent soon creates a line of cut or severance at the boundary of the solvent-treated area. When the upper has undergone lasting and its toe portion has been conformed to the shape of the last, as illustrated in Figure 4, it is also possible to remove readily the excess film material 4 beyond the marginal portion of the upper, if this has not previously been done. The excess film material may be recovered and reused in making new film material. Rather than using the stiffening agent in film form, powdered stiffening agent may, as illustrated in Figure 3, be blown or otherwise projected on the solvent-treated area of the doubler and/or lining of the upper assembly. In any event, the solvent-treated area receives stiffening medium in such a form that the medium is substantially completely dissolved or gelatinized and tends to diffuse into the fabric of the doubler and/or lining of the shoe upper assembly. Assuming that a doubler and lining fabric constitute parts of the shoe upper assembly and, after having been wet with solvent and supplied with the stiffening medium in the appropriate form, the assembly is lasted and the solvent is permitted to evaporate, the end result will be that illustrated in Figures 5 and 6. Thus, as illustrated in both these figures, the stiffening medium will diffuse into the fabric layers and this diffusion will be promoted by the pressure ap-

plied in shaping the upper assembly to the last. Such stiffening medium as remains as a coating on the lining and doubler serves to cement or bond together the successive layers constituting the shoe upper, increasing the strength of the shoe upper structure at its stiffened portion. The stiffened portion is not appreciably thicker than the unstiffened portions of the shoe and therefore assumes the lines of the last more faithfully than is the case when a stiffener blank of substantial thickness forms part of the shoe upper assembly as in prior art practice. Thus, as shown in Figure 7, the stiffened toe portion 5 of the shoe is not visibly thicker than the unstiffened vamp portion and, accordingly, there is no tendency for a ridge to be raised in the shoe upper at the vamp line.

There are many advantages inherent in the practice of stiffening shoe parts in accordance with my invention. My invention makes possible the desired stiffening effect without the introduction into the shoe upper of a blank which is apt to work loose in the shoe under the stresses of use. Moreover, the practice of my invention means that the expense incident to using additional fabric in making shoe stiffener blanks and in cutting, skiving, sorting and packing pre-formed blanks is done away with. Shoe parts stiffened in accordance with my invention are capable of withstanding the stresses of use for the life of the shoe, for the stiffening medium is integral with, or part of, the shoe upper assembly.

In using films of stiffening medium in accordance with my invention, the thickness of the film may be coordinated with the degree of stiffness desired in the finished shoe. For instance, a woman's dancing shoe need require a film of, say, cellulose acetate of only about .003 inch thickness, whereas a woman's street shoe may require two such films next to the doubler. On the other hand, a man's dress shoe may require the use of cellulose acetate film of .007 inch thickness and a man's street or work shoe may require two such films next to the doubler. In any one of these cases, however, the film required is so thin that it is promptly dissolved or gelatinized substantially completely when brought in contact with a doubler and/or lining wet with the appropriate solvent.

While I have hereinbefore described various preferred stiffening media, which lend themselves advantageously to formation and handling in film form, nevertheless, it is possible to use for the purposes of my invention various other stiffening agents. Thus, when my invention is practiced in connection with a powdered stiffening agent, it is possible to use a wide variety of stiffening agents, including not only those hereinbefore mentioned, but such other agents as resins, bitumen, hard waxes, or their equivalents, which are soluble in various organic solvents, as well as water-soluble agents like casein, dextrin, gum arabic, or the like. On the other hand, when the stiffening agent is used in film form, such other film-forming stiffening agents as casein, albumen, (e. g., blood albumen), gums, (e. g., gum shellac), and artificial resins of the class of the so-called "vinyl" and "rezyl" resins, might be employed. A casein or albumen film may be acted upon by suitable alkaline aqueous solvent media, e. g., ammoniated water, whereas gums or artificial resins like the "vinyl" and "rezyl" resins are soluble in various organic solvents, such as the hydrocarbons, alcohols, ethers, or mixed solvents of this type.

I claim:—

1. In a method of shoemaking which involves lasting a shoe upper assembly having an internal layer of fabric, those steps which comprise wetting said fabric with a solvent for stiffening agent at the desired zone, associating solid stiffening agent with said wet zone in a form conducive to a prompt and substantially complete solution of said stiffening agent, and conforming 5 said zone to the shape of the last.
2. In a method of shoemaking which involves lasting a shoe upper assembly having an internal layer of fabric, those steps which comprise wetting said fabric with a solvent for stiffening agent 10 at the desired zone, associating stiffening agent with said wet zone in thin film form conducive to a prompt and substantially complete solution of said film, and conforming said zone to the shape of the last.
3. In a method of shoemaking which involves lasting a shoe upper assembly having an internal layer of fabric, those steps which comprise wetting said fabric with a solvent for stiffening agent at the desired zone, associating stiffening agent 15 with said wet zone in a powdered form conducive to a prompt and substantially complete solution of said stiffening agent, and conforming said zone to the shape of the last.
4. In a method of shoemaking which involves 20 lasting a shoe upper assembly having an internal layer of fabric, those steps which comprise wetting the fore part of said fabric with a solvent for cellulose ester stiffening material, applying cellulose ester to said wet fore part in thin film 25 form conducive to a prompt and substantially complete solution of said film, and conforming said fore part to the shape of the last.
5. In a method of shoemaking which involves lasting a shoe upper assembly having an internal layer of fabric, those steps which comprise wetting 30 the fore part of said fabric with a solvent for cellulose acetate, applying cellulose acetate to said wet fore part in thin film form 35 conducive to a prompt and substantially complete solution of said film, and conforming said fore part to the shape of the last.
